UNITED STATES PATENT OFFICE.

JAMES COWAN MORTON, OF AUCKLAND, NEW ZEALAND.

CONDENSING APPARATUS.

Specification of Letters Patent. Patented Sept. 28, 1920.

1,354,122.

Application filed April 4, 1918, Serial No. 226,748. Renewed August 23, 1920. Serial No. 405,485.

To all whom it may concern:

Be it known that I, JAMES COWAN MORTON, a subject of His Majesty the King of the United Kingdom of Great Britain and 5 Ireland, of the S. S. *Rakaua*, Union Steamship Company Limited, of the city of Auckland in the Provincial District of Auckland and Dominion of New Zealand, have invented a new and useful Improved Condensing Apparatus, of which the following 10 is a specification.

This invention relates to condensing apparatus, employed in the distillation of salt water, and provides an improved construction of coil, the use of which results in a considerable saving of labor and cost of 15 up-keep.

According to this invention, the coil which is of helical or spiral formation consists of 20 an outer and an inner tube, the latter passing through the former for its entire length and being circular in cross section while the outer tube is preferably oval in cross section.

The coil is fastened in position at its lower 25 end only, the upper end being held loosely in a suitable support so as to provide for upward and downward and lateral movement of the coil within certain limits.

The lower end of the coil is connected to 30 a special fitting mounted at the bottom of the container, so that steam passes into the inner tube only, the latter at its upper end having communication with the outer tube.

The outer tube when the coil is fitted in 35 position connects at its lower end with passages entering a chamber in the special fitting before mentioned, which chamber has a drain therefrom adapted to be put into communication with the condenser.

40 The invention will be more particularly described with reference to the accompanying drawings, in which,

Figure 1 is a part full elevation and part 45 sectional elevation of the improved coil,

Fig. 2 is a front view of the coil end attached to the lower end of the coil and used for connecting the coil to the special fitting in the evaporator,

Fig. 3 is a cross sectional view of one of 50 the nipples of the special fitting,

Fig. 4 is a plan view of the special fitting, and

Fig. 5 a sectional view of the latter through A—B, Fig. 4.

55 Fig. 6 is a part sectional elevation showing

the coils connected to the special fitting and arranged in a tank, and

Fig. 7 is a sectional view on the line C—D of Fig. 6.

The coil consists of two tubes, an inner 60 tube 1 circular in cross section and an outer tube 2 preferably oval in cross section.

The upper end of the outer tube 2 terminates in a short vertical portion and is closed by a specially formed coil end 3 having 65 shoulders 4 and 5 thereon.

The upper end of the inner tube 1 terminates a short distance below the upper end of the outer tube 2 and has openings 6 therethrough and is therefore in communication 70 with outer tube at its upper end through the coil end 3.

The lower ends of the tubes 1 and 2 are fitted with a specially constructed coil end 2^a through which is a passage 7 communicating only with the inner tube 1 and openings 8 communicating only with the outer tube 2.

The special fitting 9 to which the coil is connected has any suitable number of externally screwed nipples 10 each of which has a passage 11 therethrough from a steam chamber 12, supplied with steam through an inlet 13. Each nipple 10 has also a passage opening 14 therethrough to correspond 80 with the passage 8 through the coil end 2^a, said passage 14 leading from a drain chamber 15 in the fitting 9 and from which there is a drain passage 16 adapted to be connected up to the condenser. 90

When the nut 17 on the coil end 2^a is screwed on to one of the nipples 10, the passage 7 through the lower coil end 2^a is placed in communication with the passage 11 through the nipple and leading from the 95 steam chamber 12 thereby enabling steam to pass into the inner tube 1. Also, the passage 8 in the coil end 2^a is put in communication with the passage 14 in the nipple. Dowel pins 14^a are provided in the nipples 10 to enter dowel pin sockets 8^a in the coil ends 2^a, and insure the passages 7 and 8 coming directly opposite the passages 11 and 14 respectively. Each nipple 10 is adapted to take a coil and the latter are secured in position at the lower end only, they preferably being kept upright by means of suitable supports loosely fitted to their upper ends between the shoulders 4 and 5. 105

Referring to Figs. 6 and 7, the coils 1 and 110

2 are shown connected to the nipples 10 of the fitting 9, this fitting being secured to the bottom plate of a tank 18. The said bottom plate has a fitting 19 for connection 5 with a steam inlet pipe. An outlet pipe 20 provides means for carrying off the pure water.

The steam derived from sea water is injected through fitting 19 into the space 13 10 whence it is distributed to the coils 1. From the upper ends of these coils, the steam passes into the outer tubes or coils 2, where it condenses. From coils 2, the water passes by way of tubes 8 and 14, into space 15 15 whence it flows, through opening 16 into the tank 18. The water may, if desired, be allowed to rise in the tank so as to cool the outer tubes 2 and thus aid in the condensation.

20 21 indicates an arm of a bracket for supporting the coil at its upper end, this connection allowing for expansion and contraction. 22 is an air vent.

25 By employing an inner and an outer tube in communication at the upper ends and out of communication at their lower ends, the chances of priming are considerably reduced owing to the hottest steam being led to the top of the coil, thereby converting to steam 30 any salt water coming in contact therewith.

Also owing to the coil having movement at its upper end it is permitted to expand and contract in any direction thereby preventing incrustations and incasings forming thereon, the oval shaped outer tube greatly 35 facilitating such expansion and contraction.

I claim:

1. A condensing apparatus consisting of sets of coils, in which each coil comprises two tubes, an inner tube of round cross section and an outer tube of oval cross section, 40 the first mentioned tube being disposed within in the last mentioned tube.

2. A condenser coil, having an outer tube and an inner tube running through said 45 outer tube, a coil end secured to the upper end of the outer tube to provide communication between the two tubes at the upper end of the coil, and a coil end secured to the lower end of the coil and having inlet and 50 outlet passages to provide communication between the two tubes at the lower end of the coil, substantially as described and illustrated.

JAMES COWAN MORTON.
